UNITED STATES PATENT OFFICE.

EDWARD MAY MUNRO, OF LONDON, ENGLAND.

SOCKET OR BASE FOR TROLLEY POLES FOR ELECTRICALLY-PROPELLED VEHICLES.

1,420,131.

Specification of Letters Patent. Patented June 20, 1922.

Application filed February 16, 1922. Serial No. 537,048.

To all whom it may concern:

Be it known that I, EDWARD MAY MUNRO, a subject of the King of England, and residing at London, in England, have invented 5 certain new and useful Improvements in the Sockets or Bases for Trolley Poles for Electrically-Propelled Vehicles, of which the following is a specification.

This invention relates to the sockets or 10 bases for trolley-poles for electrically propelled vehicles and has particular reference to an improved construction of base intended primarily for use on railless vehicles taking power from two overhead conductors and 15 employing two trolley-poles.

In such vehicles it is desirable that the poles shall be capable of swinging out as far as possible from the longitudinal centre line of the vehicle to allow the vehicle to 20 deviate from the line of the overhead conductors. These conductors are usually fairly close together and for this reason and in order to economize roof space on the vehicle, it is desirable that the two trolley-poles 25 should be near each other. Existing forms of trolley-pole bases have the disadvantage that the elevating springs, unless sunk vertically into sockets, which is not in some cases convenient or possible, are likely to foul each 30 other or the poles and thus seriously limit the swinging out of the poles.

The primary object of the present invention is the construction of a two-pole trolley base of the shallow type, i. e. without sunk 35 elevating springs, in which the poles are sufficiently close together and the elevating springs so arranged as to allow the two poles to swing out practically at right angles to the longitudinal centre line of the vehicle.

40 This is conveniently accomplished by mounting the elevating spring for each pole so that it lies outside the vertical plane of the pole and on the side remote from the other pole.

45 Preferably each pole is mounted in a socket rotatable about a horizontal axis on a table forming part of a base which is itself rotatable about a vertical axis, the stationary part of this base being mounted on the roof 50 of the vehicle. The outside end of each socket has a lug or extension acting as a crank arm and on this arm the elevating spring acts. The elevating spring may con-

veniently lie in a horizontal plane and extend forwardly in a vertical plane parallel 55 to the vertical plane in which the trolley-pole moves.

In the accompanying drawings—

Figure 1 is a plan with parts in section 60 of one construction of trolley-pole base according to this invention.

Figure 2 is a section on the line 2—2 of Figure 1.

Figure 3 is a rear elevation with parts in 65 section,

Figure 4 is a diagram showing how the 70 poles may swing out to approximately 90°, and

Figure 5 is a plan similar to Figure 1 but 75 showing a modified construction of base also according to this invention.

With reference first to Figures 1, 2 and 80 3, A are rotatable tables or bases having hollow stems A' which can turn freely in fixed sockets B mounted in any suitable way 75 as for instance by the plates B' on the roof or trolley plank C of the vehicle.

Each table is provided with a bearing A² for a short shaft or spindle D to which is secured the pole socket E. The base of the 85 trolley-pole is shown at F but in the example illustrated the socket also carries another pole F' which is however merely a strut or stay for the pole F.

The casting E forming the pole socket is 90 provided with a lug or extension E' forming a crank arm by means of which the socket and its shaft D can be turned to elevate the pole. This is accomplished by means of a spring G supported in a frame H 95 welded or otherwise secured to the outside of each table A. A lug H' at the forward end of the frame H has pivotally connected to it as at H² the end of a tube J passing back centrally within the frame H and terminating near the crank arm E'. Round this tube J is the spiral spring G with its rear end in contact with a stop or washer J' suitably held at the free end of the tube J. An inner tube or rod K passes through the tube J its 100 rear end being pivotally connected to the crank arm E' as at K' and its forward end secured by a pin or cotter K² to a head K³ slidable on the outer tube J. This head K³ forms a stop or abutment for the other 105 end of the spring G and the arrangement is

such that the spring exerts a pull on the inner tube or rod K and through it on the crank arm E' and tends to elevate the trolley-pole. The outer tube J is slotted as at 5 J² to allow the pin or cotter K² to pass through, the slot being of sufficient length to allow of the necessary movement between the outer and inner tubes and for adjustment of the strength of the spring G. This adjustment is provided for by making the stop or washer J' on the free end of the tube J adjustable by means of a nut and locknut J³ working on the screwed end of the tube J.

It will be seen that the centre line of the 15 shaft or pin D about which the trolley-socket turns, cuts the vertical centre line of the hollow stem A' of the table A. This arrangement is convenient as it allows the conductor L leading to the current collector 20 at the end of the pole F to pass straight through the stem and the pole.

The rotation of each of the tables A in 25 relation to its fixed socket B is preferably controlled by means of a cam and spring-operated rollers and in the arrangement shown in Figures 1, 2 and 3 each stem A' is provided with a cam M fixed just beneath the rotating table A. Upon these cams operate rollers or runners N mounted on 30 arms N'. These arms are attached to telescopic tubes O and O' as shown in section in Figure 1 and within the tubes is a spring P whose tension can be regulated by means of a nut and locknut P'. The action of the 35 spring tends to draw the tubes one within the other and to force the rollers N into contact with their cams M. This arrangement of cam surfaces and friction rollers or runners is such that when the vehicle is running directly beneath the conductor there is 40 no tendency to rotate the cams but when the vehicle turns out from this position and thus rotates the tables A upon which the pole sockets are mounted, the force exerted 45 by the spring-controlled friction rollers N tends to rotate the cams M and the trolley-heads further in the same direction thus relieving lateral pressure on the conductor.

The operation of this cam control is not 50 described in detail as in principle it is similar to that described in the specification of the United States Letters Patent No. 1,100,680 granted to the present applicant and the R. E. T. Construction Company Limited.

55 The construction of trolley-base shown in Figure 5 of the drawings is generally similar to that described with reference to Figures 1, 2 and 3, the chief point of difference being that in the form shown in Figure 5 the 60 rollers or runners N² which act on the cams M' are carried at the ends of leaf springs P². Each of these springs is carried in a bracket having a slotted base R. This base R has a toothed undersurface resting upon a similarly toothed portion A³ of the base plate A⁴.

By loosening the nut R² of a securing bolt which passes through the slot in the bracket R the position of the bracket may be altered relatively to the base plate to regulate the pressure of the rollers N² on the cams M'. 70 Another slight difference of construction is that in Figure 5 there is only one trolley-pole F² mounted on each of the tables the socket E² being provided with a strut or arm E³ to stiffen it, this strut or arm being 75 directly connected to the crank arm upon which the elevating spring acts.

The arrangement of the elevating springs in the form shown in Figure 5 is in all essentials the same as that described with reference to Figures 1, 2 and 3, the springs G being disposed at the side of each pole remote from the other pole and extending forwardly in a vertical plane parallel to the vertical plane in which the trolley-pole 85 moves up and down.

The diagram forming Figure 4 shows how the improved arrangement of elevating springs enables the poles F to swing out practically at right angles to the line of motion of the vehicle which in that figure is indicated by the arrow a without any fouling of the springs. In this diagram the overhead conductors from which the vehicle is taking its power are indicated at S. 95

What I claim as my invention and desire to secure by Letters Patent is:—

1. A trolley-pole base for an electrically propelled vehicle comprising two rotatable tables, a trolley-pole socket pivotally mounted on each of such tables, and a spring acting on each trolley-pole socket to elevate it, such spring being disposed at the side of each pole socket remote from the other pole socket. 100

2. A trolley-pole base for an electrically propelled vehicle comprising two rotatable tables, a trolley-pole socket pivotally mounted on a horizontal axis on each of said tables, a lug on each socket acting as a crank arm, and a spring acting on each crank arm, each of such springs lying in a horizontal plane on the outer side of its pole socket and extending forwardly in a vertical plane parallel to the vertical plane 115 in which the trolley-socket moves.

3. A trolley-pole base for an electrically propelled vehicle comprising two rotatable tables, a trolley-pole socket pivotally mounted on a horizontal axis on each of said tables, a lug on each socket acting as a crank arm, a frame attached to each table on the side remote from the other table, a tube pivotally attached to the forward end of each frame, a rod-like member pivotally 120 attached to the crank arm and extending within the tube and a spring acting between the tube and the rod-like member to raise the pole socket.

4. A trolley-pole base for an electrically 130

propelled vehicle comprising two rotatable tables, a trolley-pole socket pivotally mounted on each of such tables, a spring acting on each trolley-pole socket to elevate it, such spring being disposed at the side of each pole socket remote from the other pole

socket, cam surfaces rotating with each table, friction rollers acting on said cams and springs operating upon the rollers.

In testimony whereof I have signed my name to this specification.

EDWARD MAY MUNRO.
